RICHARD M. HEAMES, OF GROSSE POINTE, AND HAROLD STARK, OF DETROIT,
MICHIGAN

HEATING DEVICE

Application filed July 13, 1928. Serial No. 292,476.

The present invention relates in general to improvements in the art of heating, and relates more specifically to improvements in the construction and operation of heat treating furnaces, the improvements being especially applicable to heating devices where material is subjected to relatively high temperatures while it is located in a confined zone such as a receptacle or pot.

10 A general object of the invention is to provide an improved heating device which is simple and durable in construction, and wherein the heat may be more effectively applied to the material being treated, than in prior devices of a similar character.

It is common commercial practice in the art of heat treating certain kinds of metallic bodies such as cap screws and bolts, to immerse batches of the bodies in a hot solution 20 of cyanide or the like confined in a melting pot, for a definite period of time. The standard melting pots used for such purposes, are ordinarily formed of relatively low grade material which is not capable of resisting destructive corrosion resulting from the high 25 temperatures, for any great length of time. The cost of constructing these pots of higher grade corrosion resisting materials, is too great to warrant the expense, in spite of the fact that pots formed of the higher grade of 30 materials have greatly prolonged lives or periods of usefulness. The cost of such pots formed of high grade material is many times that of the standard pots which are formed 35 of low grade material.

In order to eliminate rapid destruction of such melting pots due to corrosion, the present invention contemplates the provision of jackets formed of relatively thin corrosion 40 resisting material, which may be detachably applied to the entire exterior and to a portion of the interior of standard pots constructed of relatively low grade material. These shells or jackets are formed to snugly fit the surfaces 45 of the pots which they protect, and may be manufactured at relatively low cost. When the protectors wear out, they may be renewed from time to time, thereby prolonging the life of the ordinary melting pot which is 50 formed of low grade material, manyfold, at

but very slight additional expense to the user. The renewable coverings provide a coat of armour for the pots, and may be formed of commercial sheet metal having the characteristic of effectively resisting the destructive effects of high heat.

Besides the provision of these corrosion resisting jackets for the melting pots, the present invention contemplates provision of simple means for more effectively utilizing 60 and applying heat in melting pot furnaces. This improved result is accomplished by applying the heat in series to a succession of melting pots, through controllable conduits formed and disposed to effectively apply and 65 distribute the heat. The individual pots of the series are moreover provided with special insulating closure caps which prevent undesirable escape of hot gases from the pots, but which may be readily removed to permit access to the pot interiors.

The present invention furthermore contemplates provision of means for effectively avoiding loss of material by spilling, in case the pots fail by corrosion or otherwise. 75 When such failure occurs in the standard furnaces now in use, the molten material drops into the lower portion of the heating zone and the furnace must be shut down and permitted to cool. Upon cooling, the molten material solidifies and must consequently be removed with considerable difficulty after it has solidified and adhered to the furnace structure. The removing operation frequently damages the furnace walls, besides 80 causing considerable loss of time before the furnace can again be placed in operation. In accordance with the present invention, any spilled material may be quickly removed, a new pot may be installed in place of one that 85 fails, and the furnace may be rapidly restored to operating condition, with minimum loss of time. With the improvement, all of the spilled material may be reclaimed for subsequent use, thereby eliminating waste of materials.

These and other objects and advantages resulting from the present improvement, will be apparent from the following description. A clear conception of an embodiment of 100

the several features of the present invention and of the mode of constructing and of operating furnaces in accordance therewith, may be had by referring to the drawings accompanying and forming a part of this specification, in which like reference characters designate the same or similar parts in the various views.

Fig. 1 is a horizontal section through a heating device or furnace embodying the improvements.

Fig. 2 is a longitudinal vertical section through the heating device or furnace.

Fig. 3 is a transverse vertical section through the heating device or furnace.

Fig. 4 is a vertical section through a melting pot having two of the improved protective jackets applied thereto.

The improved cyanide furnace specifically illustrated in the drawings comprises a refractory structure 13 formed of fire brick or the like and providing a series of heating zones 2, 3, 4. A pair of firing tunnels 6, 7 are disposed on opposite sides of the heating zones 2, 3, 4 and are connected with these zones by means of lateral conduits 9, 10, 11 which are of progressively increasing cross-sectional area advancing along the tunnels in the direction of the flame propagation within the tunnels 6, 7. Each of the conduits 9, 10, 11 may be provided with a shut-off gate 24 co-operating with guideways 26, for controlling the flow of hot gases to the heating zones 2, 3, 4, and additional gates 23 cooperating with transverse guideways 25 may also be provided for permitting any one of the furnaces to be shut down without interfering with the operation of the others. The opposite ends of the tunnels 6, 7 are provided with fuel injection nozzles or firing devices, and each of the heating zones 2, 3, 4, is provided with an exhaust flue 12 leading away from the lower portion of the heating chamber.

Suspended from the structure 13 and depending into each of the heating zones 2, 3, 4, is a melting pot 5 the outer portion of which is encased in a snug fitting relatively thin corrosion resisting shell 15. The portion of each pot 5, which is exposed above the molten material 18 therein, may also be provided with a protective skirt 20 formed of corrosion resisting metal and snugly fitting the adjacent surface of the pot. The protective jackets are preferably formed of sheet metal with the aid of dies, and are readily detachable from the pots 5. The metal of which the protective jackets are composed, may contain corrosion resisting ingredients such as nickel, chromium, or silicon, and the combined percentages of iron, carbon, sulphur, phosphorus and manganese contained in the alloy, should be less than ninety-five percent of the total, although better results are obtainable when the combined percentages of these ingredients is less than ninety percent

of the total. The corrosion resisting jackets or shells 15 may be retained in position in any desired manner, but they should be quickly detachable for replacement by new jackets.

Disposed above each of the melting pots 5 and resting directly upon the structure 13, is a closure cap 14. These closure caps 14 are independently and freely removable to permit access to the interior of the pots 5. The caps 14 may be provided with linings 21 formed of material which is capable of effectively withstanding relatively high temperatures, and a layer 22 of asbestos or the like serves to retain the gases and heat within the pots.

Located within each of the heating zones 2, 3, 4 directly beneath the melting pot 5 therein, is a car 16 covering substantially the entire bottom of the zones, for effecting rapid removal of spilled material 18. The cars 16 are laterally removable from within the heating zones 2, 3, 4 through side openings formed in the structure 13, and are preferably lined with refractory material such as fire brick. The openings for permitting insertion and removal of the cars 16, are preferably sealed by means of readily removable plugs 17 formed of relatively light material such as asbestos preferably confined in a shell 95 of heat resistant material, as shown in Fig. 3.

During normal operation of the improved furnace, the melting pots 5 encased within the shells 15 and lined with the skirts 20, are disposed within the heating zones 2, 3, 4 as shown in Figs. 1, 2 and 3, and fuel is injected into the tunnels 6, 7 through the nozzles 8 and is ignited therein. The gases of combustion produced by burning the fuel, pass laterally from the tunnels 6, 7 through the conduits 9, 10, 11 and are delivered tangentially against the protecting shells 15 of the pots 5. The material 18 within the pots 5 is thus kept in molten condition by the application of heat to the pots through the shells 15. Due to the corrosion resisting qualities of the protecting shells 15 and skirts 20, the exposed surfaces of these jackets are kept relatively clean at all times, thereby permitting effective transmission of the heat to the material 18 within the pots. The closure covers 14 are of special construction, and should be maintained over the pots 5 during normal operation of the furnace in order to retain the heat and the gases therein, but these caps 14 are conveniently removable when it is desired to insert a fresh batch of metallic bodies or the like in the molten material 18 within the pots. By virtue of the variation in cross-sectional area of the conduits 9, 10, 11, and also due to the arrangement of the firing nozzles 8 at opposite ends of the tunnels 6, 7, uniform distribution of the heat to all of the zones 2, 3, 4 is insured, and the flues 12 serve to deliver the spent gases from the heating zones.

If it is desired to shut down one or more of the furnaces without interfering with the normal operation of others, the conduits 9, 10, 11 and the end openings which communicate with the heating zone of the furnace which it is desired to shut down, may be readily shut off with gates 24, 23, as shown. Such shutting down of a furnace may be desirable in case of failure of the melting pot 5 therein, whereby the molten material from within the destroyed pot will be precipitated into the car 16 therebeneath. The sealing plug 17 may then be withdrawn and the car 16 containing all of the spilled material 18, may be quickly removed. The material confined within the removed car may then be reclaimed and utilized in a new melting pot inserted in the furnace in place of the device which has failed.

From the foregoing description, it will be apparent that the relatively thin corrosion resisting shells 15 not only materially prolong the lives of the melting pots 5 to which these jackets are applied, but also serve to permit more efficient transfer of heat to the material within the pots by preventing the formation of scale on the heat receiving surfaces. The skirts 20 also prolong the life of the pots 5 by eliminating destructive action of the fumes. The cover liners 21 and the asbestos layers 22 cooperating therewith effectively reduce the heat and material losses to a minimum and prolong the life of the covers to which they are applied. The liners 21 also prevent precipitation of undesirable scale, into the molten solution. The shells 15 and skirts 20 may be provided at moderate cost and should snugly fit the pots 5 in order to insure efficient transfer of heat to the material 18 within the pots. The shells 15, skirts 20 and liners 21 may be readily renewed from time to time, and may be formed of standard sheet metal having the proper corrosion resisting qualities.

By applying the heated gases through tunnels 6, 7 and distribution conduits 9, 10, 11 of progressively increasing cross-sectional areas located on opposite sides of the heating zones 2, 3, 4, effective distribution and application of the heat is insured. The provision of insulated closure caps 14 for the individual pots, also aids in the conservation of heat and in the production of maximum efficiency. The cars 16 serve to effectively catch and to facilitate removal of spilled material, and prevent adherence of the spilled material upon the furnace structure 13. The plugs 17 additionally assist in the conservation of heat, thereby producing a heating device of maximum efficiency and of highest economy.

It should be understood that it is not desired to limit the invention to the exact details of construction and operation herein shown and described, for various modifica-

tions within the scope of the claims may occur to persons skilled in the art.

It is claimed and desired to secure by Letters Patent:—

1. In combination, a relatively thick pot for directly confining molten material, a thin shell snugly fitting and covering the entire external surface of said pot, and a thin skirt snugly fitting and covering the internal surface of said pot above the normal level of molten material therein, said pot being formed of corrosive material and said shell and skirt being detachable from said pot and being formed of corrosion resistant metal.

2. In combination, a relatively thick pot for directly confining molten material, said pot having an outwardly projecting annular supporting flange at its open end, a thin shell snugly fitting and covering the entire external surface of said pot and one side of said flange, and a thin skirt snugly fitting and covering the opposite side of said flange and the internal surface of said pot above the normal level of molten material therein, said pot being formed of corrosive material and said shell and skirt being detachable from said pot and being formed of corrosion resistant metal.

In testimony whereof, the signatures of the inventors are affixed hereto.
